UNITED STATES PATENT OFFICE.

PHILLIP JEAROLD GILLEN, OF NOVA, OHIO.

RAIL ANTICREEPER.

Application filed January 25, 1928. Serial No. 249,402

This invention relates to a device for preventing the longitudinal creeping of rails on ties in a railroad track and structure.

The prime object of the invention resides in the provision of a member for gripping the rail and means abuttable with the tie for tightening the gripping means on the rail.

Another very important object of the invention resides in the provision of a device of this nature which is exceedingly simple to assemble and disassemble in respect to the rail.

Another very important object of the invention resides in the provision of a device of this nature which is disposed under the rail and therefore protected from harm.

A still further very important object of the invention resides in the provision of a device of this nature which is exceedingly simple in its construction, inexpensive to manufacture, strong and durable, thoroughly efficient and reliable in use, and otherwise well adapted to the purpose for which it is designed.

With the above and numerous other objects in view as will appear as the description proceeds, the invention resides in certain novel features of construction, and in the combination and arrangement of parts as will be hereinafter more fully described and claimed.

In the drawing:

Figure 1 is a fragmentary side elevation showing the rail and tie with my improved device assembled in respect thereto.

Figure 2 is a top plan view of the device showing a portion of the tie abutting member in section, and

Figure 3 is an end elevation of the device.

Referring to the drawing in detail, it will be seen that the numeral 5 denotes a tie upon which rests a rail 6 in the usual well known manner. The rail gripper of my improved device includes a pair of intermediately pivoted members 7 being pivoted together by a pin 8 or in any other preferred manner. Each member 7 has at one end an angularly extending hook like jaw 9 and at its other end an angularly extending rod extension 10, the jaw 9 and the extension 10 extending to the same side of the intermediate portion of the member. The jaw 9 of one of the members is offset upwardly while the rod extension of the other member is offset downwardly so that the jaws are in substantially the same plane with each other and the exten-

sions 10 are in substantially the same plane with each other.

A tie abutting member is in the form of a block 11 having lateral end extensions 12 with depending portions 14. These end extensions 12 and their extensions 14 abut the tie 5 as is clearly illustrated in Figure 1. The intermediate portion of the block is provided with a pair of bores or elongated openings 15 angularly disposed in relation to each other for receiving the rod extensions 10 so that as the gripper is forced toward the block and the block is against the tie 5 the outer side walls of the openings form incline planes tending to swing the members 7 so that the jaws 9 move toward each other and tightly grip the longitudinal edges of the base of the rail 6 and any creeping of the rail, as illustrated in Figure 1, from right to left tends to tighten the jaws still further on the rail and thereby stop said creeping.

Obviously with a few taps of the hammer on the jaw ends of the intermediate portions of the member 7 the extensions 10 may be driven into the openings 15 so as to tightly engage the jaws with the base of the rail so as to prevent creeping altogether. It will also be seen that the device may be easily disassembled by a few taps of the hammer. Of course any other implement other than a hammer may be used.

From the above detailed description it will be seen that I have devised an exceedingly simple anti-creeper attachment for rails which may be readily and easily assembled as to its parts and as to the rail and tie and may be just as easily disassembled. It will further be seen that the device is not likely to become accidentally disengaged from the rail but has a tendency to still further tightly grip the rail when the rail tends to creep in one direction.

It is thought that the construction, utility and advantages of the invention will now be clearly understood without a more detailed description thereof. The present embodiment of the invention has been disclosed in detail merely by way of example since in actual practice it attains the features of advantage enumerated as desirable in the statement of the invention and the above description. It will be apparent that changes in the details of construction, and in the combination and arrangement of parts may be resorted to without departing from the spirit

or scope of the invention as hereinafter claimed or sacrificing any of its advantages.

Having thus described my invention, what I claim as new is:

- 5 1. A device of the class described comprising a pair of members pivoted together intermediate their ends, one end of each member having a laterally disposed hook like jaw and the other end being disposed with a lateral 10 rod extension, and a block with a pair of diagonal openings extending therethrough at an angle to each other for receiving the rod extensions.
- 15 2. A device of the class described including, in combination, a tie engaging member and a rail gripping member, said rail gripping member comprising a pair of pivoted jaws with rod extensions, said tie engaging

member being provided with a pair of angularly extending openings for slidably receiving the rod extensions to cause the gripping member to tighten its jaws on the rail.

- 20 3. A device of the class described comprising a rail gripper including a pair of pivotally connected members and a tie abutting member, said tie abutting member being provided with a pair of openings extending therethrough, said openings being obliquely arranged in respect to each other to receive end portions of the pivotally connected members, so that as the tie abutting member and the axis of the pivotally connected members move in respect to each other, said pivotally connected members swing.

In testimony whereof I affix my signature.
PHILIP JEAROLD GILLEN.
